UNITED STATES PATENT OFFICE.

MELLEN N. BRAY, OF BOSTON, MASSACHUSETTS, ASSIGNOR TO TUBULAR RIVET & STUD COMPANY, OF BOSTON, MASSACHUSETTS, A CORPORATION OF MASSACHUSETTS.

MACHINE FOR SETTING FASTENERS.

Application filed August 8, 1927. Serial No. 211,354.

This invention relates to machines for setting tubular rivets and similar fasteners.

A common type of setting mechanism for fasteners of this character comprises a driver, an anvil against which the fastener is driven, and a spring pressed pilot pin normally projecting above the anvil. This pilot pin is designed to project through the work, engage the end of the rivet and lead it through the work to the surface of the anvil where the pin stops and cooperates with the anvil in expanding the end of the rivet.

In these constructions it is necessary to use pilot pins of different lengths in setting fasteners in work of different thicknesses, and it is frequently necessary, therefore to change pilot pins. Furthermore, the springs which serve to project the pilot pins cause trouble by buckling or cramping.

The present invention deals especially with these difficulties and it aims to devise a setting mechanism which will be readily adaptable to a wider range of work and will be more reliable in operation than prior constructions.

The nature of the invention will be readily understood from the following description when read in connection with the accompanying drawings, and the novel features will be particularly pointed out in the appended claims.

In the drawings,

Figure 1 is a side view, partly in cross-section, showing those parts of a fastener inserting mechanism with which the present invention is more especially concerned, and illustrating also an anvil construction embodying this invention;

Fig. 2 is a view, partly in side elevation and partly in vertical cross-section, showing the setting mechanism at substantially the completion of the fastener setting operation; and

Fig. 3 is a vertical, cross-sectional view of an anvil of a slightly different construction.

Referring first to Figs. 1 and 2, the mechanism there shown comprises a pair of spring pressed jaws 2-2, designed to receive and grip a rivet or other fastener F and hold it for the operation thereon of the driver 3. Fasteners are delivered one at a time to the jaws 2-2 by an automatic mechanism including a raceway 4, all of this

construction being old and well known in this art.

The work W is supported for the fastener setting operation on an anvil 5 which is mounted in a work supporting arm 6 with which the machine is equipped, this arm usually being adjustable vertically. A sleeve 7 which is threaded through the arm 6 so that it may be adjusted vertically with reference thereto, supports the anvil 5, and this sleeve is provided with an internal shoulder piece 8 on which the anvil rests. Nuts are threaded on the sleeve above and below the arm 6, and one of these nuts 9 at the upper end of the sleeve is provided with a set screw 10, the inner end of which enters a groove 12 in the anvil and holds it against upward movement.

The pilot pin 14, as shown in Figs. 1 and 2, is removably mounted in a plunger or shank 15, the lower part of which is screw threaded to receive adjustable nuts 16; and a strong coiled spring 17 encircles the lower part of the member 15 and bears against the nuts 16, this spring being backed up by a cap nut 18 which is threaded on to the lower end of the sleeve 7.

It will be evident that the spring 17 acts through the adjusting nuts 16 to urge the pilot pin plunger 15 upwardly and thus to project the pilot 14 above the upper surface of the anvil. The distance which the pilot projects is determined by the adjustment of the nuts 16-16 on the plunger 15.

Usually the parts are so adjusted that the upper end of the pilot pin will project very slightly above the upper surface of the work. As the fastener F is forced downwardly by the driver 3 during the setting operation its lower end strikes on the upper end of the pilot pin and thereafter the pilot pin descends with the fastener. The parts are so adjusted, however, that the lower end of the plunger 15 strikes the cap 18 when the tip of the pin 15 arrives in a position where it is flush with the cup 19 in the anvil 5, the two parts 14 and 5 cooperating at this time to form a clinching cavity. Further downward movement of the pilot pin thus is stopped, and the fastener is clinched by the final movement of the driver.

It should be observed that the pilot pin can easily be adjusted to suit the requirements of different articles of work simply by

adjusting the nuts 16—16 on the plunger 15. Also, that the pilot pin can readily be replaced whenever desired.

A slightly different embodiment of the invention is shown in Fig. 3 in which the parts similar to those shown in Figs. 1 and 2 are indicated by corresponding, but primed, numerals. In this construction the anvil 5' is smaller and it simply rests on the shoulder 8 in the sleeve 7. The pilot pin 14' is made integral with the shank or plunger 15'; and this plunger is threaded to receive nuts 16'—16' which are arranged to engage an internal shoulder 20 formed on the anvil and thus limit the projecting movement of the pin produced by the coiled spring 17'. This spring encircles a portion of the plunger 15' and is backed up by a screw threaded plug 21 corresponding to the cap nut 18.

The operation of the construction shown in Fig. 3 is like that shown in Figs. 1 and 2, the pilot pin 14' normally being projected by the spring 17' but being depressed during the driving of the fastener until its lower end strikes the plug 21. The length of the plunger is such that this occurs when the tip of the pilot pin is flush with the clinching cup 19' in the anvil. The clinching of the rivet occurs while the pin is in this position.

In both constructions cramping of the spring is prevented by the fact that it encircles the pilot pin shank or plunger. In both constructions also the pilot pins can be adjusted vertically to accommodate work of different thicknesses. Interruptions in the operation of the machine due to cramped or buckled springs thus are avoided and the necessity for a pilot pin for each thickness of work is eliminated.

While I have herein shown and described preferred embodiments of my invention, it will be understood that the invention may be embodied in other forms without departing from the spirit or scope thereof.

Having thus described my invention, what I desire to claim as new is:

1. In a machine of the character described, the combination of an anvil, a plunger slidably mounted in said anvil, a pilot pin supported on said plunger and adapted to pro-

ject through the end of said anvil, a coiled spring arranged to act on said plunger to project said pin, and screw threaded means adjustable to limit the projecting movement of said pilot pin. 55

2. In a machine of the character described, the combination of an anvil, a plunger slidably mounted in said anvil, a pilot pin supported on said plunger and adapted to project through the end of said anvil, a coiled spring for moving said plunger to project said pin, and a nut threaded on said plunger and cooperating with a part fixed with relation to the anvil to limit the projecting movement of said pilot pin. 60

3. In a machine of the character described, the combination of an anvil, a plunger slidably mounted in said anvil, a pilot pin supported on said plunger and adapted to project through the end of said anvil, a nut threaded on said plunger, a coiled spring encircling said plunger and acting on said nut in a direction to move the plunger to project said pin, and a part fixed with relation to the anvil for engaging said nut to limit said projecting movement. 70

4. In a machine of the character described, the combination of an anvil, a sleeve in which said anvil is mounted, one of said parts having an internal shoulder, a pilot pin movably mounted in said anvil, a plunger supporting said pilot pin, a coiled spring acting on said plunger to project said pilot pin, said plunger having a screw threaded exterior surface, and a nut threaded on the screw threaded portion of the plunger and arranged to engage said shoulder to limit the projecting movement of said pilot pin. 80

5. In a machine of the character described, the combination of an anvil, a pilot pin slidably mounted in said anvil and adapted to project through the end of the anvil, a plunger supporting said pilot pin, a coiled spring acting on said plunger to project said pilot pin, and two cooperating parts associated respectively with said plunger and anvil for limiting the projecting movement of said pilot pin, one of said parts being adjustable to vary the position of the end of said pilot pin when projected. 90
